UNITED STATES PATENT OFFICE.

JOSEPH MARTENA, OF NEW YORK, N. Y.

BOMB OR SHELL.

1,314,413.

Specification of Letters Patent. Patented Aug. 26, 1919.

Application filed July 13, 1918. Serial No. 244,801.

To all whom it may concern:

Be it known that I, JOSEPH MARTENA, a subject of the King of Italy, and a resident of the city of New York, borough of Manhattan, in the county and State of New York, have invented a new and Improved Bomb or Shell, of which the following is a full, clear, and exact description.

This invention relates to bombs, shells and the like and has for an object the provision of an improved construction which may be used as an aerial torpedo, mine thrower shell, or depth bomb to explode either on contact with a hard substance or at a given point in the water.

Another object in view is to provide a torpedo or shell which may be set to explode as it enters the water, or set to explode as it rises from a considerable depth toward the surface.

A still further object of the invention is to provide a shell which will be perfectly safe until the various parts have been set so that rough handling or abuse of the same will not endanger any one's life.

Another object is to provide an improved arrangement which will cause the shell to sink in case it should for any reason fail to explode after entering a given body of water.

In the accompanying drawings:

Figure 1 is a longitudinal vertical section through a shell or torpedo disclosing an embodiment of the invention, the lower part being broken away.

Fig. 2 is a detail fragmentary sectional view through Fig. 1 on line 2-2.

Fig. 3 is a horizontal sectional view through Fig. 1 on line 3-3.

Fig. 4 is a sectional view through a cartridge and associate parts shown in Fig. 3, the same being taken on line 4-4 of Fig. 3.

Fig. 5 is a sectional view similar to Fig. 1 disclosing a slightly modified form of the invention wherein electricity is used.

Fig. 6 is a fragmentary sectional view through Fig. 5 on line 6-6.

Fig. 7 is a detail fragmentary view of a pair of switching levers embodying certain features of the invention.

Fig. 8 is a fragmentary top plan view of an adjusting screw embodying certain features of the invention.

Referring to the accompanying drawings

by numerals 1 indicates a casing having an internally threaded projecting end 2 and a bottom 3. A casing 4 is threaded into the extension 2 so as to form a continuation thereof, said casing tapering to a point so as to present the usual form of shell casing. This casing contains a high explosive 5 of any desired material, as for instance picric acid and also a detonator 6 of any desired kind, as for instance mercury fulminate, or if desired a contact detonator 7 may be provided as shown in Fig. 5. A safety or protecting cap is provided for the detonator 7 which is, of course, removed before the shell is used. In forming the detonator 6 shown in Fig. 1 same is provided with a wire mesh socket 8 for receiving the wire mesh plug 9, which plug contains an end section of the fuse 10, which fuse extends through pipe 11 to the cartridge 12 near the upper part of casing 1. By this construction and arrangement whenever the cartridge 12 is operated so as to ignite the fuse the fire will pass downwardly into the casing 9 and from thence into the detonator 6 whereupon the explosive 5 will be exploded.

In Figs. 3 and 4 will be seen details of the cartridge 12, which cartridge 12 is provided with a casing 13 having a turned over end 14 fitting into an annular socket 15. An end plate 16 is connected in any suitable manner with the casing 13, said end member being provided with an aperture 17 normally covered by the pointer 18 which is rigidly secured to the support 19. When it is rotatably mounted on the support 19 it must be moved to one side so as to uncover opening 17 immediately before the shell is dropped or used. When rigidly connected with the support 19, it is rotated when the tube 20 is rotated, said tube having a square extension 21 fitting into a square socket 22 of the rod 23 carrying the contact shoe 24. The tube 20 is intended to receive the water passing through opening 17 after the shell has been submerged and direct the water through the discharge opening 25 into the interior of the casing 13. When sufficient water in the casing 13 has been provided for reaching the chemical 26, which may be any desired material, as for instance sodium, said chemical will produce a blaze for igniting

the fuse 10. Normally the rotatable shell 27 is in the way and will prevent the blaze from passing through the chemical 26 to the fuse 10 as illustrated in Fig. 3, but 5 when shoe 24 has been moved and shaft 23 rotated movement will be transmitted to the tube 20 through extension 21 and the rotatable shell 27 will be rotated so as the square extension 21 fits snugly into a square 10 opening in said shell. This will cause the opening 28 in shell 27 to be brought into register with the opening 29 in casing 13 and also in register with the opening 30 in the socket 31 which socket acts as a support 15 for the cartridge 12, tube 11 and associate parts. When the apertures are all in register the fuse 10 will naturally become ignited and will eventually cause the explosive matter to be exploded. A shutter 20 20 is slidingly mounted so as to normally shut the fuse 10 from the supporting socket 31, said shutter having an opening 33 which is brought into register with the fuse or the end opening of the pipe 11 by the rotatable sleeve 27 engaging the projection 25 34 and forcing the same downwardly as shown in Fig. 4 against the action of spring 35 as shown in Fig. 1. It will thus be seen that when the cartridge is first placed in 30 position shutter 32 is open but the rotatable shell 27 prevents any communication between the fuse and the interior of casing 13. As soon, however, as the shoe 24 has been turned casing 13 will be turned to 35 provide the proper registry and deflecting member 36 is provided for tube 20 near the bottom so as to hold the flame in the vicinity of the fuse for insuring a positive ignition thereof. It will be noted that 40 when the shoe 24 has been operated the parts are in register and will remain in register until the water has had opportunity to act on chemical 26 and produce the desired result.

45 In order to cause the shell to explode at any desired depth adjustable means have been provided for causing the shell to explode at the desired depth either going downwardly into the water or coming 50 upwardly from a considerable depth. The shell may be used as a bomb from airplanes or airships of any desired kind, or may be used as bombs dropped from an ordinary boat, or fired from a cannon, as the device 55 may be set to explode at an appreciable interval of time. In fact the bomb may be dropped from any place as it is provided with a contact detonator when hitting a hard surface, and provided with means for 60 causing it to explode when submerged in the water, as for instance an ordinary detonator. When the device is dropped from an airplane or from some place into the water the operator first opens the cover 37 which is hinged at 38 and then pulls on 65 the cable 39 until the piston 40 has been raised against the action of spring 41 until the hook and end 42 of the pawl 43 is snapped into socket 44 of piston 40. The elevated position of this structure is shown 70 in Fig. 5. The pawl 43 is pivoted at 45 and by reason of the end 42 fitting into socket 44 the parts will remain in engagement until the bar 46 strikes the extension 47 of pawl 43, so as to move the same against 75 the action of spring 48. Spring 48 is sufficiently strong to resist any tendency of the end 42 leaving socket 44 after the part has been positively moved by bar 46. The end 42, however, is rounded on the lower 80 end sufficiently to cause it to move out of the way as the piston 40 is raised whereby it may freely snap into place when coming opposite its receiving socket. As the piston 40 is raised cable 49 will be brought under 85 tension and rod 50 lifted together with a shutter 51 which normally closes the water passageway 52, this passageway being open the water will pass therein as soon as the projectile has entered a body of water and 90 will begin to act on the piston 53 for raising the same, said piston being mounted in the tubular member 54. A spring 55 resiliently resists the action of the water, said resistance being varied by the member 65 acting 95 on the spring 55. The plunger 56 is provided with a threaded section 58 fitting into the internally threaded sleeve 59, which sleeve is provided with an adjusting head 60 on the upper face, said head having a pointer 100 61 coacting with the graduations 62 shown in Fig. 8. By adjusting this head the plunger 56 may be moved upwardly or downwardly and the tension of spring 55 varied so that the projectile may be caused 105 to explode at any desired depth. In order to prevent the plunger 56 from rotating, pins 63 are rigidly connected with the upper part of tubular member 54 and positioned to extend into grooves 64 and 65 of the 110 plunger 56. As the water enters the member 54 piston 53 is raised and will move upwardly the operating rod 66 which extends through an aperture 67 provided in an offset portion of the tubular member 54. 115 The operating rod 66 is bent at 68 so as to provide a down-leg or section 69 merging into a control bar 70 and into an upstanding rod 71 to which the bar 46 is secured and also to which the square contact shoe 72 is 120 secured. This shoe is positioned as shown in Fig. 2 with one corner pointing downwardly so as to be short of engaging one side of the rotatable shoe 24 mounted on the end of rod 23. When the parts are arranged 125 as shown in the drawing shoe 72 will move upwardly and strike against the shoe 24 and move the same to one side, said move-

ment causing a partial rotation of rod 23 and consequently a partial rotation of the rotatable sleeve 27 in the cartridge 12 as heretofore described. The shoe 72 is caused 5 to travel directly upwardly by reason of the fact that the control bar 70 is arranged in a vertical slot 74 of the guide plate 75. This guide plate is provided with diagonal grooves 76 and 77 merging at 78 and also 10 merging into groove 74. When the shell is to explode on its downward travel through the water the parts are arranged as shown in the drawing and shoe 24 turned as the piston 53 and associate parts, including shoe 15 72 is elevated. When it is desired that the shell shall explode on its upward travel a switch 79 pivotally mounted on the guide plate 75 is operated manually by turning head 87 and associated parts until the switch 20 arm 80 is moved to the dotted position shown in Fig. 2 whereupon the control bar 70 will move into the groove 76 and from thence into groove 77 past the spring 81 into the upper end of groove 74 and from thence 25 downwardly through groove 74. This will cause the shoe 72 to move to one side and then upwardly past the shoe 24 without contacting therewith and then finally downwardly past said shoe in contact therewith, 30 said upward movement causing a proper side movement of shoe 24 for rotating the rod 23 and the proper parts of the cartridge 12. The switch 79 is operated by having a finger 82 which extends into the bifurcated 35 end of the arm 83 as shown in Fig. 1 and move the same from one position to another, namely from the full line position shown in Fig. 2 to the dotted line position, or in a reverse direction. Finger 82 is rigidly 40 secured to a rotatable rod 84 carried at the lower end by bracket 85, and extending through the removable upper end 86 of casing 1. The upper end of the rod 84 is provided with a head 87 having a kerf or 45 other means for receiving a tool whereby the same may be moved by the operator at any time for setting the switch 79. In order to prevent the rod 23 from moving when the shell is being handled or at the wrong 50 time, a small bracket 88 is provided which acts as a stop for limiting the movement of the arm 23 in one direction while the movable rod 89 prevents the rod 23 from moving in the opposite direction. Rod 89, 55 however, is moved longitudinally out of the way by reason of the action of spring 94 when the control bar 70 begins to move upwardly. Spring 94 is permitted to act by releasing the pivotally mounted lever 92 60 connected at 93 with the rod 89, said lever being held in a given position by the bracket 90 which in turn is held in a given lowered position by the control bar 70. When the parts are in the position shown in Fig. 1 the spring 94 is prevented from moving but 65 when member 70 rises said spring may operate so as to move bar 89 as above described. When the control bar 70 has been moved upwardly a short distance the spring 94 is then permitted to act for pulling 70 rod 89 downwardly out of the way and incidentally moving bracket 90 upwardly, said bracket being held in proper position by a suitable spring 95. When the parts are set to explode upon the upward travel 75 of the shell through the water, piston 53 will continuously move upwardly until the control rod 70 has passed spring 81 (Fig. 2) and the bar 46 has engaged the extension 47 of pawl 43 for tripping the same. When 80 this pawl has been tripped piston 40 will be released and spring 41 will move the same downwardly so as to expel the water from the chamber 96, said water passing through the passageway 97 and out through 85 the opening past gate 51. This expelling of the fluid will lighten the projectile to such an extent as to cause the same to move upwardly through the water, and as it moves upwardly the water in the tubular member 90 95 will gradually pass out through the main passageway 52, as long as gate 51 is open, and thereby allow the piston to move back toward its lowered position a sufficient distance to cause the shoe 72 to move downwardly against shoe 24 for causing the operation of the moving parts of the cartridge 12. In order to prevent a vacuum 100 in the chamber 96, and also to provide an exit for the confined air in said chamber, 100 when shell first enters the water, an air vent 99, is provided having a small opening 100 through which a spring 101 extends, said spring being secured at 102 to the casing of the vent 99 and the opposite end to a plug 103. A by-pass 104 is provided whereby 105 when the water is first entering the chamber 96, the confined air will escape through the vent until water rises to strike against plug 103, and cause the same to be turned against 110 the opening 100 for closing the opening and thereby preventing water entering the main part of the casing 1.

It is of course, evident that when the device is set for explosion on the downward travel of the shell the operation of the piston 40 is of no importance as these parts as well as the remaining parts of the shell will be destroyed by the explosion. In case the shell fails to explode on the downward travel, 115 when pawl 43 is tripped, the shell will tend to come to the surface the same as when it is set to explode on the upward travel, and when passing the predetermined depth will have a second chance to explode, piston 40 120 pressing on rod 50 will close main gate 51, and open pipe 98 through which water will 125 enter and sink the shell.

Referring to Figs. 5 and 6 a modified form of the invention will be seen in which most of the parts are identical with those shown in Fig. 1 so that only additional reference numerals will be provided for the additional parts, the entire arrangement covering the same inventive idea, but utilizing electric current for causing the explosion instead of a fuse. In this form of the invention the casing 1 is provided with an upper end 86' threaded to casing 1 in a similar manner to that shown in Fig. 1 and with the adjusting rod 84 positioned near the center of the end, operating exactly as that shown in Fig. 1. The shell 4' is provided with an upper end 105 whereby a small air chamber 106 will be provided. The detonator 108 is provided with a threaded socket for receiving the plug 109 which is provided with a sparking device of any desired kind for properly igniting the detonator. As shown in Fig. 5 the plug has one wire connected with the shoe 110 while the other wire 111 extends through pipe 112 and branch pipe 113 and is connected at 114 to a contact plug 115. The plug 115 is properly insulated so as not to ground the wire, but when closed it is in engagement with a sleeve 116 forming one of the posts of the electric battery 117. The opposite post of the battery 117 has a wire 118 connected thereto which wire extends to the upper section 119 of pipe 112 through the aperture 120 and from said aperture to the stationary contact shoe 121. By this arrangement whenever the plug 115 is closed and the shoes 110 and 121 are brought into contact current will be provided for the plug 109 so as to ignite the detonator which may be of any suitable kind. Normally the shoes 121 and 110 are held an appreciable distance apart while plug 115 is held away from the sleeve 116. As the bomb enters the water piston 53 is raised and power is transferred to rod 66 and down leg 69 to shoe 110 whereby said shoe is elevated until brought in contact with shoe 121 whereupon the circuit will be closed. As the leg 69 is raised the control bar 70 is also raised and thereby releases lever 133' so that the spring 122 may move the same downwardly pivotally and at the same time move downwardly the lever 133 to which it is slidingly pivoted as shown in Fig. 7. Lever 133 is pivotally connected with rod 139 which is slidingly supported by suitable brackets 140 which are rigidly secured to the plug 115 so that when the control bar 70 is moved upwardly a short distance spring 122 will move the parts just mentioned for closing the circuit at plug 115 whereby the parts are in condition for producing a spark in plug 109 as soon as the shoes 110 and 121 come in contact. As shown in Fig. 6 the switch plate 141 is provided similar to switch plate 75 in the pre-

ferred structure so as to switch the control bar 70 for causing shoe 110 to contact on its upward or downward travel as may be determined by the one using the bomb. As this structure has been heretofore described no additional description will be made. 70

In regard to the tubular member 54 and the adjusting parts carried in the upper part thereof, a guide 145 is provided formed as disclosed in Fig. 5 and the plunger 142 is internally threaded for receiving an exteriorly threaded rod 143 which rod carries the controlling head 60 exteriorly of the end 86'. The plunger 142 is provided with lugs 144 extending into ways or guide 145 positioned in the upper end of the well 54 whereby the plunger can rotate as the rod 143 is rotated for adjusting the tension of spring 55. 75

What I claim is:

1. A device of the character described comprising a shell, a casing at one end for receiving an explosive substance, a fuse for causing said explosive substance to explode, means for igniting said fuse, said means including a chemical capable of igniting the fuse when supplied with a quantity of water, said chemical being arranged adjacent said fuse, a tubular member for directing water from the exterior of said shell to said chemical, a double shutter mechanism for shutting off the water normally from said chemical, a contact member connected with said shutter mechanism for moving the same to an open position, a second contact member engaging the first contact mechanism for operating the same, a tubular member in communication with the water on the exterior of the shell, a piston arranged in said tubular member connected with said second mentioned contact member, and a spring for resiliently resisting the movement of said piston whereby when the pressure of water against said piston overcomes said spring said contact members will be operated for causing the water to be supplied to said chemical. 100 105 110

2. A device of the character described comprising a shell, a casing removably connected with said shell for receiving an explosive material, means for igniting said explosive material, said means including a chemical, said chemical caused to operate upon supplying water thereto, means for directing water to said chemical as the shell enters a body of water and as the shell rises from said body of water according to the position of the parts, a pointer for normally shutting off the water from said chemical, a tubular member extending from the exterior of the shell, a piston arranged in said tubular member actuated by water entering therein, a pair of contact blocks, one of which acts to operate said shutter and the other of which is operated by said piston for 115 120 125

actuating the first mentioned block, and manually operated means for shifting the block connected with the piston so as to engage the other block on its downward travel or on its upward travel.

3. A device of the character described comprising a shell, a casing arranged at one end of the shell, said casing being designed to receive an explosive material, a

10 fuse connected with said explosive material, a chemical arranged adjacent said fuse for igniting the same, means for turning on water to said chemical for causing the same to ignite said fuse, said means including a 15 pointer, a shutter normally covering said fuse, means for operating said shutter under the action of pressure of the water when the device is submerged, and a manually operated member for setting said means to operate the shutter either on its downward movement or on its upward movement.

4. A device of the character described comprising a hollow shell removably connected with said body at one end, said shell being adapted to contain an explosive matter, a fuse in contact with said explosive matter extending to a point in said body, a chemical arranged adjacent said fuse, said chemical being such that it will ignite said 30 fuse when supplied with a quantity of water, a tubular member extending to the exterior of said shell for directing water to said chemical, a means arranged at one end of said tubular member for normally shutting off the water from said chemical, a shutter normally covering said fuse, means actuated by the pressure of water for turning said shutters so as to expose the fuse to the chemical, and a regulating member with a 40 means operated by water pressure.

5. A device of the character described comprising a hollow body having an opening, a casing at one end of said body for receiving an explosive substance, a fuse connected with said explosive substance extending into said body, means for igniting said fuse arranged adjacent said opening, and a covering member normally covering said opening, a tubular member arranged 50 in said body and extending to the exterior of the body so as to permit the entrance of water when the device enters a body of water, means operated by the pressure of water entering said tubular member for moving said covering member from said opening whereby water will enter and cause said igniting means to ignite said fuse, and a rockable manually operated sleeve for shifting the position of said means so as to cause the same to move said covering member on its upward travel or on its downward travel.

6. A device of the character described comprising a hollow body, a casing at one

end of said body for receiving explosive material, a fuse connected with said explosive material, igniting means for igniting said fuse, a shutter normally arranged between said fuse and said igniting means, means including a contact block for operating said shutter, a piston for moving said block in one direction, means for directing water from the exterior of said casing to said piston for operating the same, a projection extending from said block, a spring pressed piston for moving said projection so as to move the block in the opposite direction and a shifting member for shifting the position of said block so that the same will operate said mechanism on its downward travel or on its upward travel.

7. An explosive shell or torpedo of the character described comprising a hollow body, a casing at one end of said body for receiving an explosive material, a fuse connected with said explosive material extending into said body, igniting means for igniting said fuse, a shutter normally positioned between said fuse and said igniting means, a member for moving said shutter away from between said fuse and said igniting means, a water operated piston for moving said member, a tubular chamber arranged adjacent said piston said chamber having a communication with the exterior of the body, a projection extending from said water operated piston to a position within said chamber, a spring pressed piston in said chamber designed to expel the water in said chamber and move said projection so as to shift the position of said member, a catch for normally holding the piston in said chamber against operation, an arm for releasing said catch, said arm being connected with the water operated piston, and a manually operated shifting mechanism for causing said member to operate when actuated by said water operated piston, or to operate when actuated by said projection.

8. A bomb comprising a casing containing an explosive matter, a shell, a fuse arranged in said shell provided with a projection fitting into said casing, a cartridge movably positioned in said shell supplied with means for igniting said fuse, a shutter normally arranged between said fuse and the means igniting the fuse, means for moving said shutter from between the fuse and the igniting means, and a guide for normally preventing the water from coming into contact with said igniting means.

9. A bomb comprising a shell containing explosive material and a detonator, a casing removably connected with said shell, a fuse in said casing having an extension projecting into said detonator, a removable cartridge arranged in said shell provided with a chemical for igniting said fuse when water

has been applied thereto, said cartridge having an opening in the end for receiving water when the bomb is submerged, a sliding gate for normally preventing the flame from igniting said fuse, a rotatable sleeve having an opening adapted to register with the opening

in the gate, a shaft for rotating said sleeve to bring same in register with the gate and said fuse, means for rotating said gate, and means operated by water entering said shell 10 for actuating said last mentioned means.

JOSEPH MARTENA.
